UNITED STATES PATENT OFFICE.

CHARLES V. WOERD, OF WALTHAM, MASSACHUSETTS; DANIEL O'HARA
ADMINISTRATOR OF SAID CHARLES V. WOERD, DECEASED.

MACHINE FOR POLISHING WATCH-PINIONS.

SPECIFICATION forming part of Letters Patent No. 417,377, dated December 17, 1889.

Application filed November 9, 1885. Serial No. 182,317. (No model.)

To all whom it may concern:

Be it known that I, CHARLES V. WOERD, of Waltham, in the county of Middlesex and State of Massachusetts, have invented certain 5 new and useful Improvements in Machines for Polishing Watch-Pinions, of which the following is a full, clear, and exact description.

This invention relates to a machine more 10 particularly designed for the polishing of leaves of watch-pinions to be used in a watch-movement, and will be particularly described in relation thereto; but, as will appear from the description which follows, it is in many 15 respects applicable, with a change of simple character, to the cutting of pinions.

Machines have heretofore been constructed for the purpose of polishing watch-pinions; and the main objects of the present invention 20 are to so improve on such machines as to greatly increase their working capacity as to the number of separate watch-pinions which can be polished therein within a given time, and to enable the same machine to be readily 25 changed and adapted to the polishing of watch-pinions having a different number of leaves.

The accomplishment of these ends is more 30 particularly the objects of this invention; and the invention, in substance, consists, first, in the combination, with a machine of otherwise suitable construction for the polishing of leaves of watch-pinions, of a wheel or equivalent device constructed with pockets in a 35 series around its periphery at equal distances apart and each suitably adapted to receive and hold a pinion for its leaves to be polished and the wheel arranged for an intermittent movement and for a rest after each movement, and all in such manner as to bring each 40 watch-pinion placed in said pockets successively into position for its leaves to be polished by the polishing appliances of the machine, the pinion in each pocket being suitably 45 rotated to present its separate leaves, one after another, to the action of the polishing appliances; second, in a machine of suitable construction and arrangement of parts to polish the leaves of a watch-pinion, to rotate the 50 pinion so being polished for presenting its separate leaves, one after another, to the ac-

tion of the polishing-tool, and to withdraw said polishing-tool from the pinion for said pinion to be rotated, as stated, and for removing it and replacing it with another, the 55 combination of mechanism for operating said pinion holder, polisher, and rotater, as aforesaid, constructed and arranged so as to be capable, without change thereof, of operation upon pinions of varying numbers of leaves, 60 and mechanism for communicating motion between said operating mechanisms to withdraw the polisher from and to rotate the pinion and to operate the pinion-holder, which is constructed and arranged so that by a change 65 of one of its component parts the machine, in all its operative parts to polish and rotate a pinion and to place its pinion polisher and rotator in and out of operative position and without change of any such operative parts, can be adapted for the polishing 70 of pinions having different number of leaves; third, in a mechanism such as hereinafter particularly described and claimed for rotating the watch-pinion for the presentation of 75 its several leaves to the polishing appliances; fourth, in a yielding holder which is located in each pocket of the pocket-wheel to receive and hold a watch-pinion and allow it to be rotated for presenting its separate leaves, one 80 after another, to the action of the polishing mechanism; fifth, of an arrangement, as hereinafter particularly described, of the polishing mechanism to secure its adjustment in its work upon the pinion to be polished by it and 85 to place it out of operative position without detaching it from the machine; sixth, of a polishing-tool composed of a circular metal disk and means to continuously rotate it and to reciprocate it, all as hereinafter particularly described.

In addition to the above, the invention consists of other improvements, all of which hereinafter fully appear, and are set forth in the claims.

The present improved machine is illustrated in the drawings forming part of this specification, in which—

Figure 1 is a plan view. Fig. 1^A is a detail view, as hereinafter appears. Fig. 2 is a transverse vertical section from front to rear, line 2 2, Fig. 1, with the parts back of the section-

line in elevation and some parts in vertical section, as hereinafter appears. Fig. 3 is a front elevation. Fig. 4 is a horizontal section, line 4 4, Fig. 3. Fig. 5 is a vertical section, line 5 5, Fig. 1, through the frame-work of the machine, with some working parts in cross-section and others in elevation, as hereinafter appears. Fig. 6 is a horizontal section, line 6 6, Fig. 5. Fig. 7 is a view in detail, partly in perspective and partly in vertical section, and made more particularly in illustration of the special parts of the machine, by which the machine is made capable of being readily changed for the polishing of watch-pinions having a varying number of leaves. Figs. 8, 9, and 10 are enlarged views in detail. Fig. 8 is partly in section and partly in side view, and all in illustration of the holders for the watch-pinions, of the turning devices for each pinion so held, and an adjustable holder or carrier for said pinion-turning devices, as hereinafter more fully appears.

In the drawings, A represents the frame-work of the machine, which consists, principally, of a platform or table B, supported at its front or rear by uprights C, and is otherwise suitably constructed for the support of the various working and stationary parts of the machine, as will hereinafter appear, and the whole, preferably, is carried by a bed-plate or bench in common therewith.

The polishing device of the machine consists of a continuously-rotating disk D, (shown in duplicate,) and the edge *a* of each disk is its polishing part, and it is shaped to act on the whole extent of the surfaces of the leaves of the pinions, between which it is entered, Fig. 8. Both disks D are clamped between collars E at one end of a horizontal shaft F, which is arranged to turn in suitable bearings at one (the outer) end G of the horizontal arm H, and which at its other end is pivoted and swings upon a standard J of a plate K, arranged to slide forward and backward in a dovetail groove L of the upper side of the table B, and in a direction at right angles to the axis of rotation of the polishing-disks D, and preferably made of metal. These disks both rotate in vertical and parallel planes. The shaft F of the polishing wheels or disks D has a pulley M attached to it, and this pulley is connected by belt (not shown) to a pulley (not shown) of a driving-shaft. (Not shown.)

N is a pitman-rod connecting one end of the slide-plate K with the crank-pin O of a continuously-rotating wheel or head P, which is carried by a shaft Q and turns in suitable bearing-blocks R of a standard S, and has a pulley T, by which to connect it for being driven.

The pitman-rod N, preferably and as shown, is constructed so as to be lengthened and shortened at pleasure, and again the crank-pin O of the head P, which the pitman-rod connects with the side plate K, and said head, preferably and as shown, are constructed and

arranged to enable the crank-pin to be adjusted in relation to the axis of rotation of its head P, all in a well-known manner, and therefore needing no particular description herein, and the purpose of the whole is to secure the adjustment thereof to the required or desired length of forward and backward slide of slide-plate K, and of polishing wheels or disks D, carried by it, as has been described, and to adapt the forward and backward travel of the polishing-wheels, and while under rotation, to the length of the leaves of the watch-pinions to be polished by them.

U is a thumb-screw, which screws through the hinged arm H, carrying the polishing-disks D, and has a bearing against the head *b* of the vertical lift-pin V, passing loosely through the slide-plate K, and an elongated opening (not shown) in the table B and below said table, where it rests upon the upper side of a horizontal lever X, which is fulcrumed at *d* to a fixed post Y of the table, and this lever continuously rests at its free end upon the periphery of a vertical and continuously-rotating cam-wheel Z, which is constructed and arranged and operates thereon, as hereinafter described.

The thumb-screw U holds the polishing-disks D, carried by the hinged arm H, in their proper positions or at their proper height, and by turning it in and out of said arm the height of said disks can plainly be regulated and the disks made secure at the height desired, and all for the purpose of compensating for the wear of the polishing-disks and enabling them to be placed in their proper relation to the watch-pinions to be polished in the machine, and which will hereinafter fully appear.

A² is a vertical wheel carried by a horizontal shaft B², turning in suitable bearings of vertical standards C² of the bed-plate of the machine. This wheel A² has a series of equivalent pockets D² around its periphery, and it is the carrier for the watch-pinions E², the leaves of which are to be polished, and by which to present them to the polishing-wheels one pair after another. A watch-pinion is placed and held in each pocket, as hereinafter described. This pocket and carrier-wheel A² for watch-pinions turns in a plane at right angles to the plane of rotation of the polishing-disks, and it is placed below said disks and in a position for the proper operation of two polishing-disks at one time in relation to two watch-pinions carried in separate pockets of the wheel, and as the same hereinafter fully appears.

The pocket-wheel is intermittently rotated, and it carries an index-wheel F², having around its periphery or edge a series of equidistant notches *f*, one notch for every other pocket D² of the pocket-wheel A².

g is a spring-pawl at the upper end of a vertical arm G², fulcrumed at its lower end *h* to a block H² of the bed-plate. With this

spring-pawl g engaged with a notch f of the index-wheel F^2 and the arm G^2 carrying it swung in one direction and against the tension of a spring k , connected thereto and to a fixed pin l , the index-wheel will be rotated in a corresponding direction, and on the return swing of said arm G^2 said pawl, escaping from the notch of the index-wheel with which it was engaged, then passes freely backward over the periphery of said wheel and again becomes engaged with the notch next in order in the series of notches thereof.

m is a pawl backed by a spring n and fulcrumed upon the stationary block H^2 of the bed-plate. This pawl m also is for engagement with a notch of the index-wheel and so as to hold the same against movement in either direction until it is released therefrom.

The vertical lever G^2 , carrying operating-pawl g for the index-wheel, has an arm J^2 , projecting from one side thereof and into the plane of rotation of a dog K^2 , and also an arm L^2 , projecting therefrom and in position in the swing of said lever G^2 , which carries the index-wheel forward to strike against the retaining-pawl m and release it and hold it released from the index-wheel while said wheel is being turned under the said swing of the lever G^2 , and to leave said retaining-pawl free to become again engaged with the index-wheel on the return movement of said lever, and in which movement the operating-pawl g , carried by it, is traveling backward over the periphery of the index-wheel.

The dog K^2 , before referred to, is carried by a shell M^2 , turning loosely on a horizontal shaft N^2 , which turns in suitable bearings of a standard O^2 , fixed to the common bed-plate, and of the side uprights C . This shaft N^2 also carries the cam-wheel Z , upon the edge of which, through a lever X , rests the vertical pin V , having the carrying-arm H for the polishing-disks D , resting upon it through the thumb-screw U , all as has been before described. The edge q of the cam-wheel has a series of equidistant and correspondingly-shaped cam projections or toes r , and as the cam-wheel rotates each of these toes, operating on the lever X and through lift-pin V , resting thereon, and thumb-screw U , resting on said lift-pin, lifts the hinged arm H , and through it the polishing-disks D , all of which, on the escape of the cam-toe, return to their normal position and there remain until again

lifted by the action of the cam-toe next in the order of their series as the cam-wheel continues to rotate, and so on, as before. This lifting of the hinged arm H , and through it of the polishing-disks D , is for the purpose of removing said disks from their operative and polishing position on a watch-pinion E^2 , so as to leave the watch-pinion free to be rotated to present another of its leaves to the polishing-disk, or to permit the pocket-wheel carrying them to be rotated for the purpose of presenting another pair of watch-pinions to the polishing wheel or disks, as hereinaf-

ter more fully appears. The shell M^2 , turning loosely upon the horizontal shaft N^2 , and which carries the dog K^2 for operating the lever G^2 , by and through which the index-wheel F^2 and pocket-wheel A^2 , carried by it, are intermittently rotated, as has been described, also carries a dog P^2 to lift, on each rotation of the shell M^2 , a horizontal arm Q^2 , which turns upon a stationary fulcrum-pin t , and in its normal position rests on a fixed abutment t^2 . This arm Q^2 supports two parallel and horizontal finger-rods R^2 , provided for turning the watch-pinions (the leaves of which are to be polished) in their pockets of the pocket-wheel, so as to present another leaf thereof to the action of the polishing-disks, all as will hereinafter more fully appear.

The shell M^2 has a sleeve-extension S^2 along the shaft N^2 , which carries it. This sleeve S^2 ends on the outside of one of the end uprights C of the table B , where it is provided with gear-wheel T^2 , and said shaft N^2 , outside of said gear-wheel, is provided with a corresponding gear-wheel U^2 . These two gear-wheels T^2 U^2 , one U^2 on the shaft N^2 and the other T^2 on the shell-sleeve S^2 , are geared together through a train of gear-wheels. This train consists of a gear-wheel V^2 , which is of the same size as gear-wheels T^2 U^2 , and turns on a fixed stud W^2 , and directly meshes gear-wheel U^2 , and indirectly meshes, through a smaller gear-wheel X^2 , an intermediate gear-wheel Z^2 of a stationary but adjustable stud Z^3 , and of the same size of and meshing the gear-wheel T^2 , attached to the shell M^2 , and the whole so as from the rotation of the shaft N^2 and of the cam-wheel Z to secure a rotation of the shell M^2 , and a travel of the dogs K^2 P^2 , carried by it, with a speed reduced as compared with that of the cam-wheel Z , and furthermore as and for a purpose as will hereinafter appear. The shell M^2 and cam-carrying shaft N^2 have a worm-gear Y^2 , which meshes a worm (not shown) of a shaft (not shown) driven in any suitable manner, and thus said shaft N^2 and the shell geared together, as described, are both driven with a continuous rotating motion, but the shell with a movement slower than the cam-wheel, because of the reduced gear-wheel X^2 of the train of gear-wheels described, and which gear meshes the intermediate gear-wheel Z^2 , meshing the gear-wheel T^2 of the shell, as has been described.

The finger-rods R^2 , before referred to, are parallel and in the same horizontal plane, and each is provided with a pinion-wheel B^3 , both of which mesh an intermediate gear-wheel C^3 , meshing a gear-wheel D^3 on the worm-driving shaft N^2 . Each finger-rod R^2 projects into the plane of a watch-pinion in the pocket of the watch-pinion carrier A^2 , and being polished by the polishing-disk D in position therefor, and the so-projecting part of each finger-rod has a finger a^2 , Figs. 8 and 9, radially projecting therefrom and in position as the rod rotates to work against a leaf of

the watch-pinion, and thus to turn said pinion so as to present another of its leaves to its polishing-disk, said polishing-disk at this time being lifted out of its operating position by the operation of the mechanism before described, and so as to allow the watch-pinion to be turned by the operation of the finger-rod thereon, as described. As before stated, the finger-rods R^2 are supported upon 5 an arm Q^2 , and in addition to this support each rod has a support by its pinion-wheel B^3 upon the intermediate meshing gear-wheel C^3 , and a further support at their portion toward the watch-pinion carrier of pocket-wheel A^2 in a block E^3 , Figs. 8 and 10, one 10 for each finger-rod, but both carried in a stationary common yoke or frame F^3 , and each arranged in said frame to be adjusted with set-screws G^3 , both vertically and laterally and in each direction against a spiral spring H^3 , Figs. 8 and 10, confined end to end between the block E^3 and the inside of the carrying frame or yoke F^3 , common to both of them. This arrangement of the supporting-blocks E^3 for the finger-rods R^2 in a common holder or frame F^3 , as just above described, is for the purpose of enabling each finger-rod to be adjusted in position, so as to 15 properly adapt its finger to the work it has to perform in the turning of the watch-pinion being polished and for presenting another of its leaves to the polishing-wheel. Each pocket D^2 of the pocket-wheel or watch-pinion carrier A^2 is provided with a holder for holding 20 a watch-pinion. This holder, Figs. 4 and 8, is composed of a block b^2 , having a shouldered stem c^2 , entered into and resting upon a spiral spring f^2 of a radial socket g^2 of the pocket-wheel A^2 , and of two rests h^2 , each secured by 25 a set-screw k^2 , passing through a slot l^2 of its bottom piece m^2 and screwing into said block b^2 and adapted by its upright piece n^2 as a bearing and support for the arbor of the watch-pinion and to be adjusted to and from 30 each other for watch-pinions of varying lengths of leaves.

A machine constructed of the several parts, and said parts arranged together, as has been described, when properly adjusted, and the necessary parts properly connected with the driving-power employed, operates as follows: The pocket-wheel A^2 has its pockets one after another and as they come into position provided with watch-pinions by the attendant, and being intermittently rotated, as described, 35 presents at one and the same time the watch-pinions in two of its pockets to the polishing-disks D , a watch-pinion to each disk. Each watch-pinion so presented has the edge a of a polishing-disk D , continuously rotated and vibrated forward and backward, entered into and between two of its leaves, Fig. 8, and thus all the surfaces of said leaves of each pinion which are in contact with said edge 40 a of the rotating disks are polished for the whole length of said surfaces. While this polishing is going on the pocket-wheel A^2 is

stationary, but the cam-wheel Z and dog-carrying shell M^2 are continuously rotated, as also the finger-rods R^2 , for turning the watch-pinions being polished, and the camwheel causes a lift of the polishing-disks from their operative polishing position each time a projection or toe r of the cam-wheel passes under the lifting-lever of the hinged arm H of the polishing-disks, so that at such time, by the rotation of the finger-rods R^2 , the watch-pinions can be turned around, presenting another leaf thereof to the action of the polishing-disks when they next drop into operative position 45 as the toe of the cam-wheel which lifted them, acting through the lifting-lever X and carrying-arm H of said polishing-disks, leaves said lifting-lever. This operation continues until the several leaves of the two pinions 50 being polished (the pinions having an equal number of leaves) have been presented to the action of the polishing-disks, when, by the action of the dogs $K^2 P^2$, carried by the rotating shell M^2 , the finger-rods R^2 are 55 lifted from the watch-pinions and the actuating-pawl g of the pocket-wheel is caused to rotate the pocket-wheel, bringing another pair of watch-pinions and in the next two pockets of said wheel into position for being 60 then polished, the polishing-disks being lifted to permit of this rotation of the pocket-wheel by the action of the toe of the cam-wheel Z , as has been before described. The two watch-pinions now presented have their 65 leaves polished by the polishing-disks, followed by the presentation of the remaining leaves thereof, one after another, and the same as before described, and when completed another pair of watch-pinions is presented to the polishing-disks, as before, and so on.

The cam-wheel Z , particularly illustrated, has seven toes or projections r , thus producing seven separate lifts of the polishing-disks 70 for each complete rotation of said cam-wheel, and were the dog-carrying shell M^2 , which and cam-wheel Z are under continuous rotation, geared with said cam-wheel, so as to run at the same speed therewith, there would 75 then be a movement of the watch-pinion carrier or pocket-wheel A^2 in the direction to present a pair of watch-pinions to the polishing-disks on each complete rotation of the cam-wheel, and thus the machine would be 80 adapted to the polishing of seven-leaf watch-pinions. If it is desired to polish a watch-pinion having more or less than seven leaves—as, for instance, a pinion of eight leaves—the dog-carrying wheel M^2 must be driven at a reduced rate of motion as compared with that 85 of the cam-wheel Z —that is, the dog-carrying shell must complete its rotation as the cam-wheel is working by its cam projections or toes r for the eighth time instead of the seventh, as before. This, in substance, is 90 true of any number of leaves of the watch-pinions up or down from the number of cam-operative projections or toes of the cam-

wheel—that is, for a nine-leaf watch-pinion these cam projections must operate nine times for one complete rotation of the dog-carrying shell, ten times for a ten-leaf pinion, and so on, and on the same principle of operation, should the leaves of the watch-pinion be less than seven—as, for instance, six—then the cam-wheel should operate six times for one complete rotation of the dog-carrying shell. These changes of the rotation of the dog-carrying shell in relation to the operation of the projections or toes of the cam-shell are secured by the use of a gear-wheel X^2 , of suitable size as compared with the other gear-wheels V^2 Z^2 , which are of the same size as that of the gears T^2 U^2 , attached to the shell and to the cam-wheel shaft N^2 to secure the reduction or increase, as the case may be, necessary in the rate of rotation of the dog-carrying shell as compared with the rate of rotation of the cam-wheel, and which, in the organization of the machine herein described, is always the same. For the purpose of this change the gear-wheel X^2 can be made so as to be readily attached to and detached from the gear-wheel V^2 , which rotates with it, or the two gear-wheels may be in one piece or in two pieces rigidly secured together and the change made by substituting another with the proper size of gear-wheel X^2 .

In order on any substitution of any size of gear-wheel X^2 that the proper meshing of it and of its carrying gear-wheel V^2 and of the intermediate gear-wheel Z^2 of the train of gearing shall be made, the axial stud Z^3 of the intermediate gear-wheel Z^2 is carried by an arm J^3 , which is hung upon the worm or driving shaft N^2 , carrying the cam-wheel as a center, and said arm is adapted to be fastened, after the adjustment of said intermediate gear to its proper meshing position, so as to retain said intermediate gear in such operating position. This fastening, as shown, consists of a shouldered set-screw K^3 , passing through a circular slot L^3 , concentric with the axis of the shaft N^2 , upon which the arm J^3 is hung to turn as a center and screwing into the end upright C of the table B , and on the outside of this upright the train of gearing described is located.

The forward-and-backward movement of the polishing-disks described while under rotation obviously brings them into contact with the full length of the leaves of the watch-pinions being polished.

While the machine described is polishing a pair of watch-pinions in one pair of the pockets of the pocket-wheel the attendant has all the time necessary to supply the next pair of pockets of said wheel with watch-pinions for presentation to the polishing-disks.

Only one instead of two polishing-disks may be used, and in such case the number of notches in the index-wheel F^2 should equal the number of pockets D^2 of the watch-pinion carrier A^2 , and the forward throw of the

actuating-pawl g and its action on the index-wheel should be shortened, so that on each throw thereof to move said carrier through only one-half the distance in which it is moved when a pair of polishing-disks are used, as has been described.

By substituting cutting-wheels for polishing wheels or disks D the machine described can be made capable of cutting the leaves of watch-pinions from suitable blanks presented thereto, the same as has been described for the presentation of watch-pinions to the polishing-disks, all as is obvious without further explanation.

In Figs. 1 and 2 is shown a turning-tool A^4 , suitably located for turning the edges of the polishing-disks D from time to time, as their condition from wear may require. This turning-tool is attached to a holder B^4 , arranged upon a block or carrier C^4 , to be adjusted, as may be desired, toward and away from and across the polishing-disks, so as to place it into or out of working position on either disk.

The arrangement and application of turning-tool described form no part of this invention, and are only shown and referred to so as to exhibit the machine described in a complete working form.

The suspension, Fig. 10, of the finger-rod R^3 in laterally and vertically adjustable blocks E^3 , which are backed by springs H^3 in each of said directions, enables the rod by turning the screws G^3 to be adjusted, as may be desired or necessary, to bring the operating-finger of each in proper relation to the leaves of the watch-pinion which it is to turn in the combined operation of the machine, as has been described, and to secure the necessary length of turn of the pinion—as, for illustration, a pinion of a given diameter and having seven leaves requires to be turned each time a greater distance than a pinion of the same diameter but having eight or more leaves, and so on, and in the former case the finger of the finger-rod must be brought nearer to the axis of rotation of the pinion than in the latter cases, and vice versa.

Each holder for a pinion, in its application to a pocket D^2 of the wheel A^2 , herein described, is capable of yielding to pressure upon the pinion carried by it in the operation of the polishing-disk D , while at the same time it is practically held to the action of the disk—an important feature of construction, as is obvious.

It will be observed from the description given of the present improved machine for polishing or cutting pinions that the change of the machine, as explained, for watch-pinions of varying number of leaves enables a greater or less number of lifts and falls of the pinion polisher or cutter and of operations and lifts and falls of the pinion-rotator to take place in relation to each separate operation of the machine for placing the pinion polished or cut out of and another pinion in position to be polished or cut.

The several arrangements described of the parts of this machine are most efficient ways for securing the results aimed at; but it is not intended to limit the invention to said 5 particular arrangements of said parts, nor any special arrangements thereof, for this invention as to them consists in the combination, with suitable mechanisms to secure the necessary and required operations, and particularly stated, of the pinion polisher or 10 cutter, pinion-rotator, and pinion-holder, of a mechanism to make a connection between the operative mechanisms to lift and lower the pinion polisher or cutter, and to actuate and lift and lower the pinion-rotator 15 and the operative mechanism for the pinion-holder, by means of which the movements of the pinion-holder to remove a pinion from and to place a pinion in the machine can be 20 made to occur when the pinion being removed has had all of its leaves presented for being polished or cut, and whatever may be the number of leaves in the pinion being removed as compared with the number of 25 separate lifts and falls of the pinion polisher or cutter and pinion-rotator during one complete rotation of the driving or operating shaft therefor in the present machine, and the worm driving-shaft N².

30 Having thus described my invention, what I claim, and desire to secure by Letters Patent, is—

1. In machines for polishing or cutting pinions, a circular disk-shaped pinion-leaf polishing or cutting tool, a carrier for pinions composed of a series of separate pinion-holders, each constructed substantially as described, for the reception and presentation of a pinion for rotation and the operation of 35 said tool thereon and severally arranged separately in a line, a pinion-rotator for intermittently rotating a pinion in its holder, mechanisms, substantially as described, to rotate and rectilinearly reciprocate said tool, 40 to move said pinion-carrier step by step in the line of direction of its pinion-holders, and after each movement to hold it stationary to rotate and to place said pinion-rotator into and out of engagement with the teeth of a 45 pinion in a pinion-holder and with the rotator in engagement with a pinion to rotate the pinion for a portion of its periphery, and to place said pinion cutting or polishing tool into and out of operative position in a pinion 50 in a pinion-holder, all combined and operating substantially as and for the purpose specified.

2. In machines for polishing or cutting pinions, a pinion-leaf polishing or cutting tool, 55 substantially such as described, a carrier for pinions composed of a series of separate pinion-holders, each constructed substantially as described, for the reception and presentation of a pinion for rotation and the operation thereon of said tool and severally arranged separately in a line, a pinion-rotator 60 for intermittently rotating a pinion in its

holder, mechanisms, substantially as described, to operate said tool to move said pinion-carrier step by step in the line of direction of its pinion-holders, and after each movement to hold it stationary to operate said pinion-rotator and to place it and said tool into and out of operative position upon a pinion in its holder, and a train of gearing 65 connected with a driving-shaft and said mechanism for operating said tool, pinion-carrier, and pinion-rotator, and which in part is composed of an interchangeable gear and an adjustable support for it, all combined and operating substantially as and for the purpose specified.

3. In machines for polishing or cutting pinions, a circular disk-shaped pinion-leaf polishing or cutting tool, a swinging arm at one 70 end carrying said tool, mechanisms, substantially as described, to rotate said tool and to intermittently swing said arm, and a holder constructed, substantially as described, for the reception and presentation of a pinion for rotation and the operation of said tool thereon, all combined and operating substantially as and for the purposes specified.

4. In machines for polishing or cutting pinions, a pinion-leaf polishing or cutting tool, 75 substantially such as described, mechanism, substantially as described, to operate said tool, a carrier for pinions composed of a series of separate holders, each constructed substantially as described, for the reception and presentation of a pinion for rotation and the operation of said tool thereon and severally arranged separately in a line, and mechanism to intermittently move said pinion-carrier in the line of direction of its holders, composed 80 of an index-wheel F², carried by said pinion-carrier and having notches or teeth f at predetermined distances apart, a spring-pawl g to engage them and carried by arm G², having a nose or projection J² and a spring backing it, a dog K² to work against said nose J², and means, substantially as described, to continuously revolve said dog, and thereby to move said arm G² against and leave it to the reaction of its spring, all combined and operating substantially as and for the purposes specified.

5. In machines for polishing or cutting pinions, a pinion-leaf polishing or cutting tool, 85 substantially such as described, a pinion-carrier composed of a series of separate pinion-holders, each constructed substantially as described, for the reception and presentation of a pinion for rotation and the operation of said tool thereon and severally arranged separately in a line, mechanisms, substantially as described, to operate said tool and to intermittently move said pinion-carrier and to hold it stationary after each movement, a rod R², having a finger projection to engage with and disengage from a pinion of a pinion-holder, 90 mechanisms, substantially as described, to rotate said rod, and mechanisms to place said rod R², with its finger projection, to engage

with and disengage from a pinion of a pinion-holder, mechanisms, substantially as described, to rotate said rod, and mechanism to place said rod R^2 , with its finger projection, 5 out of the line of movement of the pinion-carrier, composed of a support Q^2 for the rod, a dog P^2 to work on said support, and means, substantially as described, to continuously 10 rotate said dog, and thereby to vibrate said support, all combined and operating substantially as and for the purpose specified.

6. In machines for polishing or cutting pinions of otherwise suitable construction, in combination, a tool to polish or cut the leaves 15 of pinions, mechanism to suitably operate said tool therefor, an arm H , carrying at one and its free end said tool and at its other end hinged to a suitable support, and a continuously-rotating cam Z , having a series of equi- 20 distant cam projections r around its edge, and on which said arm H has a rest or support, substantially as described, for the purpose specified.

7. In machines for polishing or cutting pinions of otherwise suitable construction, a tool to polish or cut the leaves of pinions, mechanism to suitably operate said tool therefor, an arm H , carrying at one and its free end said tool and at its other end hinged to a suitable support and intermediate of its length 30 having an adjustable screw-pin U and up-and-down moving-pin V at its upper end supporting said arm H through its screw-pin U , a lever X , supporting said pin V , and a continuously-rotating cam Z , having a series of equi-distant cam projections r around its edge, and on which said lever X at its free end has a rest or support, substantially as described, for the purpose specified.

40 8. In machines for polishing or cutting pinions of otherwise suitable construction, in combination, a continuously-rotating rod R^2 , having a side projecting finger, mechanism to rotate said rod, a reciprocating arm Q^2 , supporting said rod, a continuously-rotating dog P^2 , and mechanism to rotate said dog, substantially as described, for the purpose specified.

9. In machines for polishing or cutting pinions of otherwise suitable construction, in 50 combination, a continuously-rotating rod R^2 , having a side projecting finger, a laterally and vertically adjustable bearing-block E^2 for said rod, and mechanism to rotate said rod, substantially as described, for the purpose 55 specified.

10. In machines for polishing or cutting pinions, embracing in their organization a pinion-leaf polishing or cutting tool capable of a reciprocating radial movement as to the 60 axis of the pinion, and a pinion-rotator capable of being moved into and out of the spaces between the leaves of the same pinion, and otherwise, both of suitable construction and operation, in combination, a continuously-rotating cam-wheel Z , having equidistant cam projections r and supporting said tool, mechanism for rotating said cam-wheel Z , a continuously-rotating dog P^2 to operate on said 65 moving pinion-carrier A^2 , provided with equidistant pockets D^2 , each suitably adapted to receive and hold a pinion for being polished or cut and rotated, an index-wheel E^2 , connected to and operating said pinion-carrier and having equidistant notches or teeth f , 70 mechanism to intermittently rotate said index-wheel, a continuously-rotating dog K^2 to actuate said mechanism for rotating said index-wheel, and a train of gearing composed of gear-wheels V^2 and X^2 , rotating as one, a 75 gear-wheel U^2 , fixed on a shaft N^2 and meshing said gear-wheel V^2 , and a gear-wheel T^2 , loose on said shaft N^2 and meshing an interchangeable gear-wheel Z^2 , having an adjustable support and in turn meshing said gear-wheel X^2 , 80 the said shaft N^2 having cam-wheel Z fixed thereto, and the said gear-wheel T^2 carrying 85 rotating dog K^2 , all substantially as described, for the purposes and operations specified.

In testimony whereof I have hereunto set 90 my hand in the presence of two subscribing witnesses.

CHAS. V. WOERD.
